MILK BOTTLE CRATE

Ewald F. Pawsat, Maysville, Ky.

Application August 20, 1934, Serial No. 740,571

2 Claims. (Cl. 220—19)

This invention is designed to accommodate milk bottles, particularly in that the handling of such bottles is usually accompanied with considerable roughness and because of the heavy character of such bottles, the crate therefor has to be of very strong construction.

An object of my invention is to produce a metal crate which accomplishes several things simultaneously, namely; a crate which stacks, one upon another, in nonslipping vertically aligned relationship by a unique structure of rods bent and welded to afford both vertical and side support of the bottles, and their separation by spaces of desirable form adapted to resist unintentional blows in loading the crate and to aid in guiding the bottles into position during this operation, as well as to accomplish through a new element a two-fold function of aligning stacked crates and strengthening the body structure thereof.

These and other objects are attained in the crate described in the following specification and illustrated in the accompanying drawing, in which:

Fig. 1 is a perspective view of a milk bottle crate embodying my invention.

Fig. 2 is a plan view of the crate shown in Fig. 1.

Fig. 3 is an end elevation of the crate I have shown.

Fig. 4 is a side elevation of the crate shown in the foregoing views of the drawing.

My improved crate is one including five principal frame members 10, 11, 12, 13 and 14, frame members 10, 11, 12 and 14 consisting merely of rectangular heavy wire formation, while member 13, also of heavy wire, is basically rectangular in shape and having upwardly extending loops 15, 16, 17 and 18 at its corners. These corner loops are so proportioned and spaced as to lie within the corners of the upper frame member 14 in position to be welded thereto. These loops, extending diagonally of the corners of frame 14, allow the bottom frame 10 of a superposed stacked crate to be placed freely over the loops, but securely preventing displacement of the crates from stacked relationship. To support the frames 10, 11, 12, 13 and 14 in properly spaced relationship, I have provided a series of vertical bars 19, both along the sides and ends of wire of smaller diameter and extending straight from top to bottom of the crate, being welded to the inside of the rectangular members 10, 11, 12 and 14, as well as to member 13 to hold them all in correctly spaced relationship, as shown. Between the loop legs on each side of upper frame member 14 and

lying next adjacent thereto are the four especially shaped vertically disposed bars 20 which have central portions 20' extending toward the corners of frames 11 and 12 and also welded thereto to strengthen these corners adjacent to the bends thereof. In this manner the loops are avoided at the top of the crate and clearance afforded at the bottom of the crate for the upstanding loops of the crate stacked immediately beneath.

On the ends of the crate and occupying more of a middle position thereon relatively to the straight bars 19, are special bars 21 bent at their upper ends to lie apart far enough to enable portions 22 of the upper frame members 14 to be used as handles.

Supported by and welded to frame 12 are longitudinal bars 23 extending from end to end of the frame, and transverse bars 24 extending from side to side of the frame, the bars being welded together at their points of crossing. These crossed bars, properly spaced, constitute the spacers defining the spaces in which bottles are received. As an additional feature these longitudinal bars 23 are flattened vertically at points 25 midway between the bars 24 and the ends of the frame 12 to strengthen the grid against vertical blows when loading the crate, as well as, because of their reduced thickness, of enabling the bottles to be entered within their respective spaces more readily.

On frame 11 identically the same type of space-defining grid is provided, in the forms of bars 26 extending longitudinally immediately beneath bars 23, and bars 27 extending transversely immediately beneath bars 24, all points of crossing and frame contact being welded.

To support the bottles in the spaces formed by the grids, a bottom of crossed bars supported by and welded to frame 10 is provided. This bottom consists of transverse bars 28 supporting spaced longitudinal bars 29 which are out of alignment with the grid bars so that the bottles rest upon them, especially shaped longitudinal bottom bottle-supporting bars 30 terminating in bent ends welded to the sides of frame 10 instead of its ends as are bars 29. This is done for the special purpose of clearing the bottom corners of frame 10 for the reception of the loops 15, 16, 17 and 18 of a crate stacked immediately beneath.

It will thus be seen that I have produced a novel crate in which a series of rigid rectangular frame members of heavy wire constitute the body of the crate, with one of these frame members

- shaped in a most unique manner to provide the interlocking corner lugs or loops by means of which the crates may be interlocked as it were, thereby permitting of their being stacked. Attention is called also to the manner in which the two upper frame members are made to carry the blows and strains placed on the loops by bringing these loops within the upper frame member and welding them thereto at their points of contact. As has been said, the vertical flattening of longitudinal spacer bars 23 and 26 at points 25 contributes materially to the strength and bottle-guiding characteristics of the grids, this also being a desirable feature of my invention. Having thus described my invention as above, setting forth features of distinction therein, other details which render my disclosure new and novel will at once, be apparent. Having thus described my invention what I claim is:
1. A milk bottle crate comprising a series of horizontal rectangular heavy wire frames, a series of less heavy bars, spaced apart vertically within and crossing the frame wires around the inside thereof, welded thereto and supporting the frames in spaced relation above one another, crossed

horizontal bars supported by and welded to the lowermost frame to sustain the weight of bottles within the crate, crossed horizontal bars supported by and welded to intermediate frames in grid formation to form bottle spaces within the crate, and stacking loops formed on the corners of an intermediate frame, extending upwardly through and welded to the corners of the upper frame, the bars in the region of the lower corners of the crate having a formation designed to clear the corner for the reception of the stacking loops of a crate stacked immediate beneath. 10

2. A milk bottle crate comprising a series of horizontal frames, vertical bars spaced apart and welded to the frames in spacing relationship, bottom bars extending in grid fashion from side to side and end to end of the bottom frame and welded thereto, the corners of an intermediate frame adjacent to the upper frame being bent upward to form upstanding loops lying within 20 and welded to the corners of the upper frame to form stacking lugs adapted to lie within the corners of the bottom frame of a crate next above in a stack. 15
